US00D899421S

(12) **United States Design Patent** (10) Patent No.: **US D899,421 S**
Deb et al. (45) Date of Patent: **** Oct. 20, 2020**

(54) **QUANTUM KEY SECURE ELECTRONIC DEVICE**

(71) Applicant: **Cognizant Technology Solutions India Pvt. Ltd.**, Chennai (IN)

(72) Inventors: **Sandeep Deb**, Pune (IN); **Indranil Mitra**, London (GB); **Aan Singh Chauhan**, Pune (IN)

(73) Assignee: **COGNIZANT TECHNOLOGY SOLUTIONS INDIA PVT. LTD.**, Chennai (IN)

(**) Term: **15 Years**

(21) Appl. No.: **29/693,211**

(22) Filed: **May 31, 2019**

(51) LOC (12) Cl. **14-02**

(52) U.S. Cl.

USPC **D14/313**

(58) **Field of Classification Search**

USPC D14/313, 348-355, 498-511; D10/104.1
CPC **H05K 7/1485-1495**

(57) **CLAIM**

We claim, the ornamental design for a quantum key secure electronic device, as shown and described.

DESCRIPTION

FIG. 1 is a perspective view of a quantum key secure electronic device, showing our new design;

FIG. 2 is a top view thereof;

FIG. 3 is a side view thereof;

FIG. 4 is bottom view thereof;

FIG. 5 is a side view thereof, taken from the opposite of FIG. 3;

FIG. 6 is a front view thereof;

FIG. 7 is a rear view thereof; and,

FIG. 8 is a another perspective view thereof.

Where, portions shown in broken lines form no part of the claimed design.

1 Claim, 5 Drawing Sheets

FIG. 1

FIG. 2

FIG. 3

FIG. 4**FIG. 5**

FIG. 6

FIG. 7

FIG. 8
